UNITED STATES PATENT OFFICE.

JULIAN H. RIVERS, OF ST. LOUIS, MISSOURI, ASSIGNOR TO KAESMANN-RIVERS DEVELOPMENT COMPANY, OF ST. LOUIS, MISSOURI, A CORPORATION OF MISSOURI.

LAUNDRY-DRIER.

1,011,373.

Specification of Letters Patent.

Patented Dec. 12, 1911.

Application filed July 26, 1909. Serial No. 509,471.

To all whom it may concern:

Be it known that I, JULIAN H. RIVERS, a citizen of the United States, residing at St. Louis, Missouri, have invented a new and 5 useful Laundry-Drier, of which the following is a specification.

This invention relates to laundry driers, and its object is to produce an apparatus whereby steam or hot air may be forced to 10 circulate and pass through the articles to be dried to perform drying functions.

The apparatus the subject matter of this invention may also be applied to other uses than a drier in laundries, and mention may 15 be made at this point that I do not restrict myself to specific use, but desire to claim the invention for all purposes.

In the embodiment shown in the accompanying drawings Figure 1 is an elevation, 20 partially in section, showing the arrangement of a preferred construction. Fig. 2 is an elevation, showing the arrangement of the door whereby access may be had for insertion, and removal of the articles.

25 The tank 1 may be of any suitable dimensions and shape, and constructed of any available material, but is preferably of metal, and is supported by posts or standards 2. A cover 3 hermetically seals the upper end of the tank. A rod or shaft 4, extending across the top, is connected at its ends with vertical links 5, the lower ends of which are connected with the sides of a hopper bottom 6. The shaft 4 is arranged 30 so that when rotated it will raise and lower the links 5 and thereby the bottom. This operation may be effected by the use of cams 7 attached to said shaft 4, or by arranging the shaft in the form of an eccentrically 35 pivoted roller which, when rotated, would produce the same effect. If desired guides 40 may be utilized to prevent lateral displacement of the shaft.

At one side of the tank, by hermetic hinge 45 construction 9, a door 10 is mounted through which access may be had to the interior of the tank. The bottom 6 is constructed so that its upper edge will embrace the bottom of the tank and the lower edge of the door 50 10 when in closed adjustment, thereby to hold the parts in proper relation and hermetically close the lower end of the tank. A tray 11, composed of side walls and a reticulated bottom, is removably supported 55 upon brackets 12, in the lower end of the

tank and is of such size that it may be passed through the door 10 for removal and insertion. This tray is intended to contain the articles to be dried or subjected to treatment, and the reticulated bottom permits 60 the water and moisture to be forced therethrough into the hopper bottom 6, whence it may be removed or drawn off through the valve controlled pipe 13.

A steam or air inlet pipe 14 enters the tank 1 near its upper end, and slightly below the plane of the lower edge of the deflector plate 15 attached to the top. A valve 16 controls the passage of the steam or air through said pipe. A separate valve controlled pipe 17 opens into the tank below the pipe 14.

In operation as a laundry appliance the tray 11 containing the articles to be treated is passed through the door 10 and onto the 75 supports 12. The door is then closed, and the shaft 4 is rotated to raise the bottom 6 to embrace the lower end of the tank and hermetically close the same. The steam or air (or other agent), is then admitted, under pressure, through the pipe 14 and is forced through the articles in the tray, and outwardly through the pipe 13 driving out the water and moisture. The moisture drops into the bottom 6 and will be removed 80 through the outlet pipe 13 when the valve in said pipe is opened to permit free escape of the air or steam from the tank. Water may be admitted in advance of the air or steam through the pipe 17 and withdrawn 85 through the pipe 13 in advance of the steam or air. The deflector 15 acts as a conveyer along oblique surfaces of which the accumulating drops of moisture will flow to the outer edge of said shield; thence the 90 moisture drops outside the tray 11, and falls into the bottom 6 without passing through the contents of the tray.

It is obvious that the invention may be applied to different uses, and that there may 100 be variations from the structure described without departure from the spirit and scope of the invention. I do not restrict myself to specific features, but

What I claim and desire to secure by Letters Patent is:—

1. A drier comprising a drying chamber, a water inlet passage, a separate valve controlled steam inlet opening into said chamber, an outlet passage, a tray between said 110

outlet passage and said inlet passages, and a deflector device in said chamber, substantially as specified.

2. A drier comprising a drying chamber, 5 an inlet passage, an outlet passage, a valve controlling said outlet passage, a tray having a perforated bottom between said passages, and a deflector above said tray having its edges extending beyond the sides of 10 said tray whereby moisture from said deflector will be delivered outside of said tray, substantially as specified.

3. A drier comprising a drying chamber, a water inlet to said chamber, a separate 15 steam inlet to said chamber, a valve controlling said steam inlet, a tray below said inlets, a movable bottom below said tray, and an outlet passage from said movable bottom, substantially as specified.

20 4. A drier comprising a drying chamber, a movable bottom for said chamber, a door for said chamber, and means for holding said bottom in engagement with said door effectively to lock said door in closed position, substantially as specified.

25 5. A drier comprising a drying chamber, a door, a bottom locking said door in closed position, an outlet from said bottom, means for moving said bottom to unlock said door, 30 and a tray in said chamber removable through said door, substantially as specified.

6. A drier comprising a chamber, a door to said chamber, a bottom locking said door in closed position, links supporting said bot-

tom, a shaft operable to move said links effectively to raise and lower said bottom to release said door, guides holding said shaft from displacement, and a tray in said chamber removable through said door, substantially as specified.

40 7. A drier comprising a drying chamber, a door, a bottom locking said door in closed position, an outlet from said bottom, and means for moving said bottom to unlock said door, substantially as specified.

45 8. A drier comprising a drying chamber, a door to said chamber, a bottom locking said door in closed position, links supporting said bottom and means for operating said links to move said bottom, substantially as 50 specified.

9. A drier comprising a drying chamber, a tray in said chamber, a door to said chamber, a bottom locking said door, links supporting said bottom, a shaft supporting said 55 links, and cams on said shaft whereby said links and said bottom will be raised and lowered when said shaft is rotated, substantially as specified.

In testimony whereof I have hereunto set 60 my hand to this specification this 17 day of July, 1909, in the presence of two subscribing witnesses.
